Patented June 11, 1918.

UNITED STATES PATENT OFFICE.

JOHN C. MAGNESS, OF NEW YORK, N. Y., ASSIGNOR, BY DIRECT AND MESNE ASSIGNMENTS, TO ATLAS AUTO SPECIALTIES CORPORATION, OF NEW YORK, N. Y., A CORPORATION OF NEW YORK.

CARBURETER ATTACHMENT.

1,269,104.

Specification of Letters Patent. Patented June 11, 1918.

Application filed April 12, 1917. Serial No. 161,589.

To all whom it may concern:

Be it known that I, JOHN C. MAGNESS, a citizen of the United States, and resident of the borough of Manhattan, in the city 5 and State of New York, have invented a new and useful Improvement in Carbureter Attachments, of which the following is a specification.

This invention relates to an improvement 10 in carbureter attachments and more specifically to a device for providing a certain amount of moist air for mixture with the motive fuel in the carbureter manifold.

Another object consists in providing such 15 a device which has means for regulating the flow of the moist air to the manifold so that the amount of moist air supplied may increase as the demand exercised upon the carbureter by the engine to which it is attached increases.

A further object consists in providing certain improvements in the form, construction and arrangement of the several parts whereby the above mentioned and other objects 25 may be effectively attained.

A practical embodiment of my invention is represented in the accompanying drawings, in which—

Figure 1 represents a front view, partly 30 broken away, of the complete device,

Fig. 2 represents a vertical section taken in the plane of the line II—II of Fig. 1, looking in the direction of the arrows, and

Fig. 3 represents a horizontal section 35 taken in the plane of the line III—III of Fig. 1, looking in the direction of the arrows.

The device comprises a vessel or a tank 1, which may be of any suitable form. In the 40 present instance, it is shown as cylindrical and composed of sheet material, which may appropriately be brass, copper, and the like. The exact size of the tank is not an essential of my invention, but I have found that a 45 cylinder 6 inches in height and $4\frac{1}{2}$ inches in diameter works very well in connection with a carbureter suitable for a four-cylinder, four-cycle internal combustion engine having a bore of $3\frac{1}{4}$ inches and a stroke of $4\frac{1}{4}$ 50 inches.

The tank 1 may be supported by a bracket 2 secured by means of screws 3 to the side of the engine 4, or to the frame of the vehicle or the dashboard. I prefer to locate it closely adjacent to the carbureter. It will 55 be understood that the arms of the bracket 2 are firmly attached to the tank 1 as by brazing or soldering.

The tank 1 has, near the lower part thereof, a narrow, arcuate compartment 5, which 60 is formed of similar sheet material suitably secured, as by brazing, to a portion of the inner wall of the tank 1. This compartment 5 is closed at the top and bottom; but it is provided in its side wall, near its lower 65 extremity, with a horizontal series of apertures 6, which open communication between the compartment 5 and the interior of the tank 1. Furthermore, the wall of the tank 1, within the extent of the compartment 5, 70 and near the top of the latter, has a hole 7 which permits communication to be established between the surrounding atmosphere and the interior of the compartment 5.

In a tank of the dimensions above indicated, I have found that the apertures 6 may be sixteen in number and one-sixteenth of an inch in diameter. They may also be spaced one-sixteenth of an inch apart. The hole 7 may be three-sixteenths of an inch in 80 diameter. In giving these dimensions I do not intend to imply that they circumscribe the operative limits of the invention. They are stated merely as a guide which may be followed in order to insure satisfactory results.

The tank 1 also has a hole in the top thereof in which is fitted a bent pipe 8 which serves the double purpose of providing means for partly filling the tank with water, 90 denoted by 9; and of subsequently acting as an air inlet channel, which I choose to call the "dry" air inlet, in contradistinction to the outlet for the air after it has been moistened, which will be hereinafter described. 95 The pipe 8 may conveniently have an inside diameter of $\frac{1}{4}$ of an inch.

A nipple 10 is secured, as by brazing or soldering, to the upper side wall of the tank 1, which nipple has both ends threaded; the 100

outer one for engagement with a pipe, (not shown) leading to the carbureter intake manifold, and the other for engagement with a valve cage 11. The channel through 5 the nipple 10 may appropriately be $\frac{1}{4}$ of an inch in diameter, and the pipe used in connecting it to the manifold may be of similar size.

Within the cage 11, a conical valve 12 is 10 fitted to slide in a bearing 13 that is screwed into the upper ends of the cage 11, which latter protrudes through the top of the tank 1. The extremity of the stem of the valve 12 carries one or more nuts 14, which, together with the bearing 13, provide abutments for an expansion coil spring 15 that normally tends to hold the valve 12 at the limit of its movement away from its seat, as shown in full lines, Fig. 2. The limit of 20 this movement is determined by the engagement of the body of the valve with the under face of the bearing 13, as also exhibited in full lines, Fig. 2.

The valve cage 11 also has an inlet port 25 16, which may be $\frac{1}{4}$ of an inch in diameter, and which provides communication between the interior of the cage 11 and the interior of the tank 1.

A suitable dome or cover 17 may be 30 forced over the bearing 13 and cage 11, and held in position by frictional contact therewith, in order to protect the protruding stem of the valve and spring 15. The bottom of the tank 1 may also have a suitable drain plug 18.

In installing a device, it is merely necessary to fasten it by the bracket 2, in a suitable position adjacent the carbureter, and then connect the projecting end of the 40 nipple 10, by means of a suitable pipe, with the intake manifold at a point above the carbureter. After the device has been installed and connected, it may be partly filled with water, the maximum height of 45 which is regulated by the hole 7 in the tank 1, which, for this purpose, acts as an overflow. Thus, the operator may simply pour water in through the pipe 8, until he finds the same overflowing through the hole 7; 50 at which time the filling may cease.

In operation, when the motor is started, the suction generated by one or more of the pistons will be effective in the intake manifold in a well understood manner, and this 55 will also produce a suction in the pipe leading to the manifold from the nipple 10. This suction will draw the valve 12 down onto its seat, against the action of the spring 15, as shown in dotted lines, Fig. 2. The 60 closing of the valve 12 is desirable in order to prevent, at this juncture, an influx of air, which would unduly weaken the mixture and handicap the starting of the motor. As soon as the motor is well in operation, it

will be drawing a relatively large amount 65 of air and hydrocarbon fuel through the carbureter, by reason of the fact that the throttle is considerably open. This action serves to decrease the suction in the pipe leading to the nipple 10, and thus allows 70 the spring 15 to draw the valve 12 slightly away from its seat.

In this position of the parts, the suction in the nipple 10 will be transmitted to the interior of the tank 1, which will 75 result in drawing air inwardly through the hole 7, thence downwardly through the water in the compartment 5, thence through the apertures 6 into the water 9 in the tank 1, and thence up through the air space 80 in the tank 1 to the inlet port 16 in the valve cage 11. This air, which has become moist during its passage through the water 9, will be drawn beneath the valve 12 and through the nipple 10 into the intake 85 manifold, to be mingled there with the motive "gas" generated in the carbureter; after which the whole will be taken into the cylinders of the engine for combustion. It will be noted that, while the operation 90 just described is going on, additional "dry" air is drawn into the tank 1 through the pipe 8, which "dry" air mingles with the very moist air before the same passes through the port 16 into the valve cage 11 95 and thence onward. The opening through the pipe 8 also serves the purpose of preventing the suction in the tank 1 from becoming so great as to cause the water itself to "boil" up and pass into the cage 11 and 100 the pipe leading therefrom to the manifold.

As the speed of the engine increases, the suction is, as is well understood, increased in the carbureter, which latter is almost invariably provided with means for enlarging 105 the apertures through which the atmospheric air is drawn, as the said suction is increased. This action serves to further decrease the suction generated in the pipe from the carbureter manifold to the nipple 10; 110 and this decrease in suction permits the spring 15 to draw the valve 12 farther away from its seat; thus increasing the volume of moist air which is drawn from the tank 1 into the intake manifold. It will be seen 115 that the way in which the valve is arranged enables the same to automatically compensate (within limits) for the increase and decrease in the speed of the engine, so as to provide more or less of the moist air to the motive fluid mixture, respectively. In practice, I have found that the valve 12 is actually closed at the time of starting the motor; that as the engine gains speed, it gradually opens until it is well clear of the 120 seat, and that it remains in substantially this position while the engine is operating at comparatively high speed. As the

throttle is moved toward closed position, and the speed of the engine decreases, the valve returns toward its seat; and, at very low motor speeds, it is closed. The function of this valve has been found to be very desirable.

Although I have put this device through extensive and careful experimentation under varying conditions of use, and have data as to its effectiveness, it is not deemed appropriate to specifically set forth the same; but I may say that the device has been found to be highly effective in increasing the power developed by the engine from a given amount of hydrocarbon fuel, such as gasoline, and that it also serves the purpose of preventing the formation of carbon deposits upon the reciprocating parts and combustion chamber walls of the engine, as well as having an active tendency to remove any such deposits as may have accumulated.

As indicated before, I have given dimensions with some degree of exactness in order that suitable relative sizes and arrangements may be apparent, but it is to be understood that various changes may be resorted to in the form, construction, arrangement, size and relative proportions of the several parts without departing from the spirit and scope of my invention; hence I do not intend to be limited to the details herein shown and described, except as they may be specifically included in the claims.

What I claim is:

35 1. A device of the character described comprising a liquid holding tank, a compartment adjacent said tank, said compartment being in communication with the tank and with the atmosphere, and a dry air inlet spaced from the bottom of said tank.

2. A device of the character described comprising a liquid holding tank, a compartment adjacent said tank, said compartment being in communication with the tank and with the atmosphere, a dry air inlet spaced from the bottom of said tank, and a moist air outlet also spaced from the bottom of said tank.

3. A device of the character described comprising a liquid holding tank, a compartment adjacent said tank, said compartment being in communication with the tank and with the atmosphere, and a dry air inlet near the top of said tank.

4. A device of the character described comprising a liquid holding tank, a compartment adjacent said tank, said compartment being in communication with the tank and with the atmosphere, a dry air inlet near the top of said tank, and a moist air outlet also near the top of said tank.

5. A device of the character described comprising a liquid holding tank, a compartment adjacent said tank, said compartment being in communication with the tank and with the atmosphere, a dry air inlet near the top of said tank, and a moist air outlet also near the top of said tank.

ment being in communication with the tank and with the atmosphere, a dry air inlet spaced from the bottom of the tank, and a valve controlled moist air outlet also spaced from the bottom of the tank.

6. A device of the character described comprising a liquid holding tank, a compartment adjacent said tank, said compartment being in communication with the tank and with the atmosphere, a dry air inlet near the top of the tank and a valve controlled moist air outlet also near the top of the tank.

7. A device of the character described comprising a cylindrical liquid holding tank, and a narrow, arcuate compartment located at one side of the tank and near its bottom, said compartment having a hole near its bottom for opening communication with the tank, and a hole near its top for opening communication with the atmosphere.

8. A device of the character described comprising a cylindrical liquid holding tank, and a narrow, arcuate compartment located at one side of the tank and near its bottom, said compartment having a series of holes near its bottom for opening communication with the tank, and a hole near its top for opening communication with the atmosphere.

9. A device of the character described comprising a cylindrical liquid holding tank, and a narrow, arcuate compartment located at one side of the tank and near its bottom, said compartment having a series of holes near its bottom for opening communication with the tank, a hole near its top for opening communication with the atmosphere, and a dry air inlet near the top of the tank.

10. A device of the character described comprising a liquid holding tank, a compartment adjacent the bottom of said tank, said compartment being in communication with the tank near the bottom of the compartment and in communication with the atmosphere near the top of the compartment, a dry air inlet near the top of the tank, and a moist air outlet near the top of the tank.

11. A device of the character described comprising a liquid holding tank, a compartment adjacent the bottom of said tank, said compartment being in communication with the tank near the bottom of the compartment and in communication with the atmosphere near the top of the compartment, a dry air inlet near the top of the tank, and a valve controlled moist air outlet near the top of the tank.

12. A device of the character described comprising a liquid holding tank, a compartment adjacent the bottom of said tank, said compartment being in communication with the tank near the bottom of the compartment and in communication with the atmosphere.

mosphere near the top of the compartment, a dry air inlet near the top of the tank, and a valve controlled moist air outlet near the top of the tank, for automatically regulating the flow of moist air from the tank.

5. 13. A device of the character described comprising a liquid holding tank, a compartment adjacent said tank, said compartment

being in communication with the tank and with the atmosphere, a dry air inlet near the top of said tank, and a tube extending from said dry air inlet into the tank.

In testimony that I claim the foregoing as my invention I have signed my name this 9th day of April 1917.

JOHN C. MAGNESS.
